UNITED STATES PATENT OFFICE.

CYRUS E. JOHNSTON, OF WILKIE, SASKATCHEWAN, CANADA.

GENERATOR.

1,259,104.

Specification of Letters Patent. Patented Mar. 12, 1918.

Application filed July 29, 1916. Serial No. 112,153.

To all whom it may concern:

Be it known that I, CYRUS E. JOHNSTON, a citizen of the United States of America, residing at Wilkie, in the Province of Saskatchewan and Dominion of Canada, have invented certain new and useful Improvements in Generators, of which the following is a specification.

This invention relates to generators, and 10 more particularly to a steam generator specially adapted for use in connection with a turbine engine.

The turbine engine, because of its high efficiency, simplicity, and lack of vibration, 15 is peculiarly suited for use in connection with automobiles and similar vehicles. The chief reason why this engine is not used for these purposes is due to the fact that its operation necessitates the provision of a 20 comparatively large and heavy boiler and means for generating steam in this boiler. One of the main objects of my invention is to provide a generator of light construction and high efficiency by means of which 25 steam may be supplied direct to the turbine engine. A further object is to provide a generator in which the products of combustion, as well as the steam generated, may be used for operating the turbine. A further 30 object is to provide a generator specially constructed to burn either liquid or gaseous fluid. Further objects will appear from the detailed description.

In the drawings:—

35 Figure 1 is a vertical central sectional view through the generator,

Fig. 2 is a front view, and

Fig. 3 is a section on line 3—3 of Fig. 2.

The numeral 1 designates a cylindrical 40 boiler formed, at its upper end, with a steam dome 2 having a safety valve 3 of any suitable construction. A pipe 4 communicates with the steam dome and is connected to a turbine, not shown, so as to supply operating fluid to the same. Near the lower end 45 of boiler 1, and extending transversely thereof, I secure a cylindrical combustion chamber 5. At the inner end of this chamber, and communicating therewith, is secured a receiving chamber or header 6. A plurality of flue pipes 7 have their inner ends shrunk into the front wall of the header 6 and their outer ends secured in the inner wall of an approximately circular 55 chamber 8 mounted near the front of cylinder 1. This chamber is of approximately

elongated U-shape in vertical cross section and has its upper end open so as to establish direct communication with the interior of the upper end of the boiler. By this 60 means, the products of combustion pass freely from the combustion chamber 5 through the tubes 7 and chamber 8 into the upper part of the boiler, and thence into the steam dome 2 and pipe 4 to the engine. 65

A flanged cylindrical mixing chamber 9 is threaded into the outer end of the combustion chamber and has its inner end 10 provided with a plurality of relatively small perforations. This mixing chamber communicates, at its outer end, with an air pipe 11 in which is interposed an air supply valve 12. The stem 13 of this valve is extended inward and has its inner end squared so as to fit into the squared aperture provided at 75 the apex of a bell crank lever 14. The lower arm 15 of this lever is pivotally connected to a pull rod 16 which may be connected to a hand lever positioned on the steering wheel, or in any other suitable location, 80 within easy reach of the person operating the automobile. The other arm 17 of the bell crank lever is pivoted to the lower end of the lower section 18 of a connecting rod. This section 18 is of tubular construction 85 and slidably receives a rod 19, the upper end of which is pivoted to a block 20. The parts 18 and 19 of the connecting rod may be adjusted by means of a binding screw 21 threaded through a collar 22 integral with 90 the upper end of the section 18, so as to vary the effective length of the connecting rod.

The block 20 is mounted on an arm 23 and adjustable thereon by means of a binding screw 24 threaded therethrough. The lower end of arm 23 is fixedly secured on the outer end of stem 25 of a needle valve 26 threaded into a short pipe 27, the inner end of which is threaded into a nipple 28 100 projecting from the wall of boiler 1. A fuel supply pipe 29 communicates at its upper end with the pipe 27, and at its lower end with a fuel supply tank 30. The fuel in this tank is fed under pressure into the 105 pipe 27, the flow of the fuel being controlled by the needle valve 26. The air pipe 11 communicates with an air tank 31 so as to feed air into the mixing chamber 9 under pressure, the flow of this air being controlled by the valve 12. Due to the connections between the valves 12 and 26, these 110

two valves can be simultaneously adjusted by means of the rod 16 so as to vary the supply of fuel flowing into the combustion chamber. It will be evident that, by adjusting the position of the block 20 on the arm 23, the amount of fuel which is fed into the mixing chamber in proportion to the air may be varied to suit the particular fuel used. When the block has been adjusted as described, the proportions of air and fuel will remain constant for the different variations or adjustments of the two valves by means of the rod 16.

The inner end of the short pipe 27 with which the fuel supply pipe communicates, is connected to a vaporizing coil 32 mounted in the vaporizing coil chamber 8 at the front of the boiler 1. The lower end of this coil communicates with a pipe 33 which discharges downwardly into a neck 34 of the mixing chamber 9 through the aperture 35 in the top thereof. In using a liquid fuel, such as kerosene, gasolene, or the like, the fuel is thoroughly vaporized by the heat from the products of combustion as it passes through the coil 32. This vaporized fuel is discharged in a vertical stream of current across the neck 34 of the mixing chamber. At the same time, air is admitted under pressure from the tank 31, by means of the pipe 11, in a plane at right angles to the stream of vaporized fuel. The air acts to thoroughly dissociate and atomize the fuel, and the air and fuel flow into the mixing chamber where they are thoroughly and intimately mixed. This mixture is forced through the perforated inner end 10 of the mixing chamber into the combustion chamber 5 where it is ignited by means of a spark plug 36 which is threaded into the bottom of boiler 1 and connected to a battery by means of the wires 37, in the usual manner. When the mixture is ignited in the combustion chamber it gives rise to intense heat, the products of combustion flowing through the flue pipes 7 and vaporizing coil chamber 8 as previously described. The water which is fed into the boiler 1 by means of the water supply pipe 38 circulates freely about the combustion chamber 5, pipes 7, header 6 and chamber 8. This water absorbs a large amount of the heat which is generated in the combustion chamber and quickly becomes converted into steam. This steam and the products of combustion flow into the steam dome 2 and from there are taken direct to the turbine engine so as to operate the same. By this construction, both the steam generated by the combustion of the fuel mixture and the products of combustion are utilized. As the boiler 1 is entirely closed this steam may be raised to the desired pressure for operating purposes in the boiler itself. In this connection, it is necessary, of course, that the fuel and the air be fed into the com-

bustion chamber at a pressure slightly greater than the pressure of the steam. The mixture of fuel and air is injected under pressure into the combustion chamber, the perforated inner end of the mixing chamber serving to effectually prevent back-firing into the same.

As will be noted from Figs. 1 and 3 of the drawings, the combustion chamber 5, flue pipes 7, and vaporizing coil chamber 8, are all relatively spaced so as to permit free circulation of the water in the boiler. This water absorbs the heat generated by the combustion of the fuel so as to effectually prevent any of the elements of the generator being injured by heating to an undesirable degree. Also, this absorption of heat serves to reduce the temperature of the products of combustion flowing into the steam dome 2 sufficiently to avoid injury to the turbine from those products which flow into the same with the steam.

The boiler 1 is incased in a heavy layer or coating 39 of asbestos or other suitable heat insulating material. This coating is secured in position by an outer casing 40 of wood, sheet metal, or other suitable material.

The boiler 1 is provided with a suitable steam gage 41 and a water gage 42. The boiler is also provided, at its lower end, with a drain-cock 43 for draining and cleaning purposes.

While I have described my generator as using a liquid fuel, it will be evident that it can also be used in connection with a gaseous fluid. When a fuel of this character is used, the vaporizing coil 32 may be omitted. In this connection it is to be noted that my generator is well adapted for use in connection with an oxy-hydrogen burner. The oxygen and hydrogen would be supplied to the mixing chamber from suitable tanks, in the same manner as the liquid fuel and air, in the proportion of one part of the former to two parts of the latter. This mixture, when ignited, would produce a very intense heat, the products of combustion being water vapor or superheated steam, which would readily combine with the steam generated in the boiler 1 and pass into the turbine. By this means all danger of injury to the turbine, due to carbon passing into the same with the products of combustion, would be eliminated.

It will be obvious that changes may be made in the construction and arrangement of the different parts of my invention without departing from the field and scope of the same, and I intend to include all such changes as fall within the scope of the appended claims, in this application, in which a preferred form only of my invention is disclosed.

What I claim is:—

1. In generators, a combustion chamber, a

- mixing chamber secured in the combustion chamber and having its inner end of foraminous construction, an air supply pipe communicating with the mixing chamber 5 at the outer end thereof so as to direct a current of air inwardly axially of the mixing chamber, a fuel supply pipe communicating with the mixing chamber in advance of the air supply pipe and adapted to 10 direct a stream of fuel into the mixing chamber radially of the same, a vaporizing coil chamber, a vaporizing coil mounted in said chamber and interposed in said fuel supply pipe, and means for conducting the 15 products of combustion from the combustion chamber to the vaporizing coil chamber so as to vaporize the fuel in the coil.
2. In a generator of the character described, the combination of a boiler, a combustion chamber mounted therein, a mixing chamber mounted in the combustion chamber and having its inner end of foraminous construction, a vaporizing coil chamber mounted within the boiler, a vaporizing coil 25 mounted in said chamber and communicating with the mixing chamber, means for supplying fuel to the said coil, means for supplying air to the mixing chamber, and means for conducting the products of combustion 30 from the combustion chamber to the vaporizing coil chamber, said vaporizing coil chamber being open at its upper end and communicating directly with the interior of the boiler.
- 35 3. In generators, a boiler, a combustion chamber mounted within the boiler, a vaporizing coil chamber mounted within the boiler and open at its top communicating directly with the interior of the boiler, a fuel vaporizing coil mounted in said coil chamber and communicating with the combustion chamber and a plurality of spaced flue tubes communicating with the combustion chamber and the vaporizing coil chamber, said tubes, combustion chamber, and vaporizing coil chamber being all mounted in spaced relation whereby free circulation of water in the boiler about and between all of said elements is permitted.
4. In generators, a boiler, a combustion chamber mounted within the boiler, a vaporizing coil chamber mounted within the boiler and open at its top communicating directly with the interior of the boiler, a mixing chamber communicating with said combustion chamber, a vaporizing coil mounted in said vaporizing coil chamber and communicating with said mixing chamber, means for supplying fuel to said coil, a header carried by the combustion chamber at the inner end 50 thereof, and a plurality of flue tubes communicating with said header and said vaporizing coil chamber.

In testimony whereof I affix my signature in presence of two witnesses.

CYRUS E. JOHNSTON.
